CENTRALIZED TRAFFIC CONTROLLING
SYSTEM FOR RAILROADSEdwin O. Blodgett, Rochester, N. Y., assignor to
General Railway Signal Company, Rochester,
N. Y.

Application April 13, 1933, Serial No. 665,990

22 Claims. (Cl. 246—3)

This invention relates to railway centralized traffic controlling systems, and more particularly to a system known as the direct control type as distinguished from a selector or coded type of system.

It is proposed, in accordance with the present invention, to provide a means for controlling a remote power operated track switch by distinctively selecting the direction of current in a first line circuit, and to control the traffic over the track switch by conditioning the same control line circuit in a manner that a subsequent distinctive selection of the direction of current therein may be effective to govern traffic over that track switch in either direction. It is also proposed to provide a means for communicating over a second line circuit an indication of the operated position of the track switch, the clear or stop indication displayed by the signals associated with that track switch, and the presence or absence of a train on a detector section of track. It is further proposed to provide interlocking circuit means to prevent improper operations of the system and still retain sufficient operating flexibility to permit efficient governing of traffic movements.

Other objects, purposes and characteristic features of the invention will appear as the description thereof progresses, during which, references will be made to the accompanying drawing which illustrates in a diagrammatic and conventional manner one specific embodiment of the present invention which is susceptible of considerable modifications or adaptations in practice depending on the type of controls required and the character and number of indications which are considered advantageous in the particular application.

In the accompanying drawing, a complete communicating system is shown for transmitting controls and indications between a typical outlying field station and the apparatus at the control office which is associated with this field station. It is to be understood, however, that in a practical application of this system, there will be considerable distance between a field station and the control office, and that it is necessary to extend only three wires over this distance namely the control line wire CL, the indication line wire IL and the common line wire C. The wire C may be the common wire for the complete centralized traffic controlling system, if so desired, or may be the common wire for only one station.

In systems having several outlying field stations, two line wires, such as CL and IL, will of

course be required to connect each of these field stations with the control office, and the field station apparatus as well as the control office apparatus which are designated by the legend on the drawing will also be duplicated for each of the outlying stations.

A typical section of track over which traffic may be controlled in accordance with the present invention is diagrammatically shown at the field station as including a track switch TS arranged to route traffic either over a main or diverging route as shown. This track switch TS is operated by a switch machine SM and suitable wayside signals ES, WS and WSA are shown in the conventional manner as governing traffic movements over this section of track.

A portion of a track diagram which simulates the typical section of actual track shown at the field station is illustrated at the control office. This track diagram includes an indicating light OS for indicating the occupancy of a section of track including the track switch and a similar indicating light SK is provided for indicating the clearing of any one of the signals ES, WS or WSA.

A signal control lever SGL is employed at the control office which is operable to three positions, namely west, stop and east as indicated respectively by the references W, S and E.

A switch control lever SML is also provided which is operable to two positions, N and R, for setting up a normal and reverse control for the switch machine SM. Suitable contacts are shown in the conventional manner as operated in accordance with the various positions of the control levers SGL and SML, and a third indicating light COR is provided for indicating when the operated position of the track switch TS corresponds to the position of the control lever SML.

The various relays at both the control office and the field station are shown in the conventional manner, and it may be here mentioned that the relays SA, NIS and RIS at the control office are shown with heavy base lines to indicate that these relays are slower acting than other relays not indicated in this manner. The relay M at the field station is the conventional signal repeating relay arranged in the local signalling circuits, (not shown) to be normally energized whenever all the signals ES, WS and WSA are displaying stop indications, but to be de-energized whenever any one of the signals displays a clear indication. The relay TR is the conventionally arranged track relay associated with a normally energized section of track including the track switch TS, and the relay

WP is a conventional switch repeating relay arranged to operate its polar contact to positions corresponding to the operated positions of the track switch TS and to drop its neutral contacts whenever the switch is not in either extreme locked position by circuits not shown herein but which may be arranged as fully described in the patent to C. S. Bushnell No. 1,517,236 granted November 25, 1924.

10 The control and indicating line circuits are to be energized from a suitable alternating current source of energy. This source of energy is indicated as being connected to the primary of a transformer TR at the control office while one side 15 of the secondary of this transformer is connected to the common line wire C and the other side is connected to one side of each of two oppositely arranged asymmetric units or rectifiers RA and RB. At the field station, two similar rectifiers 20 RA¹ and RB¹ are each connected at one side to the common wire C, and these rectifiers at both the control office and at the field station may be of any suitable type of asymmetric unit, such as the usual copper oxide unit, the electrolytic rectifying unit, the vacuum tube unit, or any other type 25 which may be readily adapted to the rectification of low current values.

The symbols (+) and (−) are employed to indicate opposite terminals of a source of energy at 30 both the control office and at the field station, and when a battery is employed for this source of energy, the symbols represent the positive and negative terminals thereof, or if alternating current is employed, the symbols may be considered 35 as representing relatively opposite instantaneous polarities. Inasmuch as the line relays NI and RI at the control office and RC and NC at the field station are to be energized by half cycles of alternating current selected by the rectifying units RA and RB, a means for adapting these 40 relays to operate with greatest efficiency on current of such characteristics may be necessary. For example, a special design of the magnetic circuit may be provided in these line relays to effect 45 a "hold over" of the magnetic attraction of the armature between successive energizations of the windings by successive half cycles of the alternating current.

Operation

50 In the accompanying drawing, the switch control lever SML is shown in its normal position N which effects the energization of relay NC at the field station by half cycles of alternating current which are of a definite polarity (which for convenience may be termed (+) polarity). The circuit for energizing relay NC may be traced from the upper terminal of the secondary of transformer TR, through the rectifying unit RA to bus A, contact 5 of lever SML in its normal position N, wire 6, back contact 7 of relay SA, wires 8 and 9, control line wire CL, wire 10, through the windings of relay NC, wire 11, bus A¹ through the rectifying unit RA¹, and back to the lower terminal of the secondary of transformer TR over the common line wire C.

The track switch TS at the field station is also shown in the normal operated position in accordance with the position of its control lever 70 SML which effects the energization of relay NI at the control office by half cycles of alternating current which are of a definite polarity (which may be termed (+) polarity). The energizing circuit for relay NI may be traced from the upper terminal of the secondary of transformer

TR, through the rectifying unit RA to bus A, wire 20, through the windings of relay NI, wire 19, indicating line wire IL, neutral front contact 18 of relay WP, polar contact 16 of relay WP in its left hand position, wires 15 and 14, front contact 13 of relay M, wire 12, bus A¹, through the rectifying unit RA¹ and back to the lower terminal of transformer TR by the common line wire C. The energization of relay NI then energizes its stick repeating relay NIS over a circuit from 10 (+), front contact 21 of relay NI, wire 22, back contact 23 of relay RIS, wires 24 and 25, through the winding of relay NIS to (−).

Now, considering that the operator desiring to reverse the track switch TS to route traffic upon 15 the passing siding, moves the switch control lever SML to position R. With the switch control lever SML in its reverse position R and relay NIS energized, an indication at the control office that the position of the switch control lever is out of 20 correspondence with the position of the track switch is now displayed by energizing the correspondence light COR over a circuit from (+), back contact 41 of relay RIS, wire 42, front contact 43 of relay NIS, wires 44 and 45, contact 46 25 of lever SML in its reverse position R, wire 47, through the indicated light COR to (−).

The moving of the lever SML to position R shifts the energization of the control line circuit from bus A to bus B thereby changing the polarity of the half cycles of alternating current to a (−) polarity which releases relay NC and energizes relay RC which is rendered responsive to this (−) polarity by rectifier RB¹. This circuit for energizing relay RC may be traced from the lower terminal of the secondary of transformer TR, over line wire C, through the rectifying unit RB¹ to bus B', wire 26, through the winding of relay RC, wire 27, control line wire CL, wires 9 and 8, back contact 7 of relay SA, wire 6, contact 5 of lever SML in its reverse position R, bus B, through the rectifying unit RB to the upper terminal of the secondary of transformer TR. With relay NC de-energized and relay RC energized, a circuit is completed for operating the 45 switch machine SM in a manner to reverse the track switch TS, which circuit may be traced from (+), back contact 28 of relay CGS, wire 29, front contact 30 of relay RC, back contact 31 of relay NC, reverse control wire R, through the 50 operating mechanism of the switch machine SM to (−).

It is to be understood that suitable approach locking means is to be provided in the control circuits for the switch machine SM, but in order to simplify the drawing, such locking means have been omitted. It was previously stated that the neutral contacts of relay WP are in their de-energized position whenever the track switch TS is not in either extreme locked position, and consequently during a change in position of the track switch the opening of the neutral front contact 18 of relay WP will de-energize the indicating line wire IL. The opening of front contact 18 obviously drops relay NI which in turn drops relay NIS, but the indicating light COR is maintained energized over a circuit from (+), back contact 54 of relay RIS, wire 55, back contact 56 of relay NIS, wires 57 and 47, through the light COR to (−). It is thus obvious that an unlocked condition of the switch TS will be indicated at any time by dropping relays NIS and RIS and energizing the indicating light COR at the control office.

When the reverse operation of the track switch 75

has been completed the polar contacts of relay WP are shifted to their extreme right hand position and the neutral front contact 17 is closed. A circuit is then completed for energizing relay 5 RI at the control office with half cycles of alternating current of a reverse polarity (which may be termed (-) polarity), and this energizing circuit may be traced from the lower terminal of the secondary of transformer TR, over the common line wire C through the rectifying unit RB¹ to bus B¹, wire 38, front contact 39 of relay M, wire 37, polar contact 16 of relay WP in its right hand position, wire 17, neutral front contact 18 of relay WP, indicating line wire IL, wire 36, 10 through the windings of relay RI, wire 35, bus B, through the rectifying unit RB to the upper terminal of the secondary of transformer TR. The energization of relay RI now effects the picking up of relay RIS over a circuit from (+), 15 front contact 48 of relay RI, wire 49, back contact 50 of relay NIS, wires 51 and 52, through the windings of relay RIS to (-). The picking up of relay RIS now indicates at the control office that the track switch TS has operated into correspondence with the reverse position R of the 20 lever SML by extinguishing the indicating light COR as will be seen from observing its previously traced energizing circuits.

It will now be considered that, after receiving 25 an indication of the reverse operation of the switch TS, the operator at the control office moves the signal control lever SGL to position E for allowing an east bound train movement onto the passing siding. The control line circuit including line wire CL is now energized with alternating current, or in other words the half cycles of alternating current of the (+) polarity are applied through rectifiers RA and RA¹ to pick up relay NC at the field station, and these half cycles of alternating current of the (+) polarity 30 are alternated with half cycles of alternating current of the (-) polarity through rectifiers RB and RB¹ to also pick up relay RC.

The energizing circuit for relay RC may be traced from the lower terminal of the secondary 40 of transformer TR, over the common line wire C, through the rectifier RB¹ to bus B¹, wire 26, through the windings of relay RC, wire 27, control line wire CL, wire 9, back contact 60 of relay NIS, wire 61, front contact 62 of relay RIS, wire 45 63, contact 64 of the control lever SML in its reverse position R, wires 65 and 66, contact 67 of lever SGL in position E, bus B, through the rectifier RB to the upper terminal of the secondary 50 of transformer TR. Likewise, the energizing circuit for relay NC may be traced from the upper terminal of the secondary of transformer TR, through the rectifier RA to bus A, wire 68, contact 69 of the control lever SGL in position E, 55 wire 70, back contact 71 of relay SA, wires 72 and 65, contact 64 of the control lever SML in position R, wire 63, front contact 62 of relay RIS, wire 61, back contact 60 of relay NIS, wire 9, control line wire CL, wire 10, through the windings of relay NC, wire 11, bus A¹, through the rectifier RA¹, and back to the lower terminal of the secondary of transformer TR over the common line 60 wire C.

With both relays RC and NC energized, a circuit is completed for picking up relay CGS at the field station from (+), front contact 74 of relay NC, front contact 75 of relay RC, through the winding of relay CGS to (-). However, during the energization of the control line circuit with 75 alternating plus (+) and minus (-) polarities,

the slow acting relay SA at the control office is energized over a circuit from (+), back contact 43 of relay NIS, wire 42, front contact 41 of relay RIS, wires 76 and 77, contact 78 of the lever SML in position R, wire 79, contact 80 of lever SGL in position E, wires 81 and 82, through the windings of relay SA to (-).

After a predetermined period of energization, the relay SA picks up and removes the half cycles of alternating current of the (+) polarity from the control line circuit by opening its back contact 71, which obviously drops relay NC at the field station but maintains relay RC energized due to the half cycles of alternating current of the (-) polarity maintained on the line circuit through contact 67 of the control lever SGL. Although the previously traced energizing circuit for relay CGS is now interrupted by the dropping of relay NC, a stick circuit is effective to hold up this relay from (+), front contact 83 of relay RC, front contact 84 of relay CGS, through the windings of relay CGS to (-). A circuit is now completed at the field station for selecting signal ES from (+), front contact 28 of relay CGS, wires 85 and 86, contact 87 of relay NC, front contact 88 of relay RC, through the local signaling circuits as represented by the dotted line 89 to the signal ES.

It will now be obvious that a west bound signal may be selected in a similar manner, or that is, with the signal control lever SGL operated to its clear west bound position W, the control line circuit CL is energized for a predetermined period of time with alternating (+) and (-) polarities of energy to pick up both relays RC and NC, but after the relay SA at the control office picks up, the (-) polarity of half cycles of alternating current will then be removed to drop relay RC and select relay NC. A relay CGS being selected by the previous application of both (+) and (-) polarities will now be maintained energized by the previously traced stick circuit now completed by contact 90 of relay NC, and an obvious circuit for selecting the west bound signals according to the position of the track switch repeating relay WP will then be effective to allow a west bound train movement dependent of course on local conditions.

A signal repeating relay M at the field station is dropped as previously stated whenever any one of the signals is displaying a clear indication, and keeping in mind the previous energization of the indicating line circuit with (-) polarity of half cycles of alternating current to pick up relay RI and its stick repeating relay RIS at the control office, it will be obvious from the drawing that this dropping of relay M changes the polarity of the half cycles of alternating current from (-) to (+) by the dropping of contact 39 which shifts the line wire LI from bus B¹ to bus A¹. This quick changing from (-) to (+) polarity of half cycles of alternating current in the indicating line circuit obviously drops relay RI and picks up relay NI, and inasmuch as there is substantially no intervening time between the dropping of relay RI and the picking up of relay NI, the relay RIS having slow releasing characteristics does not drop due to a stick circuit completed by the picking up of relay NI. This stick circuit may be traced from (+), front contact 21 of relay NI, wire 22, front contact 23 of relay RIS, wires 91 and 52, through the windings of relay RIS to (-).

This out-of-correspondence condition between the energization of the line relays at the control

office and their respective repeating relays, or that is, with relay RIS energized but with relay NI energized instead of relay RI, an indication that a signal is clear at the field station is given 5 at the control office by energizing the indicating light SK over a circuit from (+), back contact 43 of relay NIS, wire 42, front contact 41 of relay RIS, wires 76 and 92, front contact 93 of relay NI, back contact 94 of relay RI, wire 95, through 10 the indicating light SK to (-).

It will further be obvious that a signal clearing at the field station when the track switch TS is in its normal position energizes the signal indicating light SK at the control office in much 15 the same manner, except that in this case, the relays NI and NIS are first energized, but the dropping of contact 13 of relay M changes the energization from the relay NI to the relay RI. This sticks up relay NIS over a circuit from (+), 20 front contact 48 of relay RI, wire 49, front contact 50 of relay NIS, wires 96 and 25, through the winding of relay NIS to (-). With relays RI and NIS energized, an indication of a clear 25 signal is given by energizing the indicating light SK over a circuit from (+), back contact 41 of relay RIS, wire 42, front contact 43 of relay NIS, wires 44, 97 and 98, front contact 94 of relay RI, back contact 93 of relay NI, wire 95, through the indicating light SK to (-).

30 Having now described the way in which the track switch TS may be controlled from the control office and the manner in which a signal governing movements over this switch may be cleared, it will be considered that a train enters 35 the section of track including the switch TS thereby dropping the relay TR. The contact 16 of relay WP which selects the particular polarity of half cycles of alternating current to indicate the position of the track switch is then connected in multiple with a contact 100 of relay WP by back contact 101 of relay TR. It may be seen from the drawing that this contact 100 is connected in an opposite manner to contact 16, and consequently regardless of the position 40 of the contacts of relay WP, the wires 14 and 37 are each connected to the line wire IL whenever the relay TR is de-energized. Thus, the occupancy of the track section controlling relay TR is effective to apply full cycles of alternating 45 current through both rectifiers RA¹ and RB¹ to the line wire IL, or for example, with the track relay TR de-energized and relays WP and M in the position shown, the line wire IL is energized with half cycles of alternating current of the 50 55 (-) polarity through front contact 18 of relay WP, wires 17 and 102, back contact 101 of relay TR, contact 100 of relay WP in its left hand position, wires 103 and 37, front contact 39 of relay M, wire 38 to bus B¹ and rectifier RB¹, and likewise the line wire IL is energized with 60 half cycles of the (+) polarity through front contact 18 of relay WP, wire 17, contact 16 of relay WP in its left hand position, wires 15 and 14, front contact 13 of relay M, wire 12 to bus A¹ and rectifier RA¹.

The half cycles of alternating current of the plus (+) polarity are effective at the control office to pick up relay NI, and simultaneously 70 the half cycles of alternating current of the minus (-) polarity alternately therewith are effective to pick up relay RI. An indication of the occupancy of the track section at the field station is now given at the control office by energizing the indicating light OS over a circuit 75

from (+), front contact 104 of relay NI, front contact 105 of relay RI, wire 99, through the light OS to (-).

It will be obvious that, when the track relay TR is dropped, the signal governing traffic movements over the track section are placed at stop by the local block signalling circuits thereby picking up relay M, and at the control office, the signal indicating light SK is de-energized at either back contacts 93 or 94 of relays NI or 10 RI respectively, which are now both energized. However, an indication of the correspondence between the track switch and the control lever SML is retained by the energization of relay RIS, and as soon as the train progresses out 15 of the track section, the relay TR will again pick up to allow the energization of the indicating line circuit to be selected in accordance with the operated position of the track switch TS, which in this case will be the reverse position 20 to select relay RI and maintain relay NIS energized.

If during the existence of a clear signal indication at the field station the operator desires to place such a signal at stop, the signal control 25 lever SGL is returned to the stop position S which obviously de-energizes the control line circuit at contact 67 and also de-energizes the slow releasing relay SA at contact 80. However the relay SA having slow acting characteristics does not immediately drop, and during its dropping time, relays RC and NC at the field station are both de-energized which drops relay CGS thereby opening the signal control circuit at contact 28. When the relay SA drops, the control line 30 circuit is again closed by back contact 1 of relay SA, and the energization of the control line circuit is again selected in accordance with the 35 position of the switch control lever SML.

It will be obvious that the control circuit set 40 up by moving the signal control lever SGL to either the clear east bound or clear west bound position may only be effective when an indication of the operated position of the track switch is present at the control office which corresponds to the position of a switch control lever SML, or in other words, the selected energization of 45 relays NIS and RIS in regard to the position of contact 60 and 62 must correspond to the position of contact 64 of lever SML before the signal control circuit can be completed. Also, to prevent the cancelling of a switch control which has not been executed by a subsequent movement of the signal control lever, the same 50 correspondence arrangement is employed in series with the energizing circuit for relay SA, or that is, the selected energization of relays NIS and RIS in regard to the position of contacts 43 and 41 must correspond to the position of 55 the switch control lever contact 78 before the relay SA may be picked up to open the switch control circuit and back contact 7.

This arrangement of checking the correspondence between the indicated switch position and the switch control lever before a signal control 60 can be effective obviously permits a route to be aligned by the operator by positioning the switch control lever and immediately thereafter moving the signal control lever to set up a control for a clear signal in the selected direction, inasmuch as such signal control will not be effective until an indication has been received at the control office that the track switch has operated 65 70 75

a circuit completed when both the series line relays are picked up.

The above rather specific description of one form of the present invention is given solely by the 5 way of example, and is not intended in any manner whatsoever in a limiting sense. It is also to be understood that various modifications, adaptations, and alterations may be applied to meet the requirements of practice, without in any manner 10 departing from the spirit or scope of the present invention except as limited by the appended claims.

Having thus described my invention, what I claim is:—

15 1. In a centralized traffic controlling system for railroads, a control office, a field station, a line circuit connecting said control office and said field station, a means for controlling a first device at said field station by selecting the direction 20 of pulsating current in said line circuit, a means for controlling a second device at said field station by selecting the direction of pulsating current in said line circuit, and means for changing the control of said first device to the control 25 of said second device by momentarily energizing said line circuit with alternating current.

2. In a centralized traffic controlling system for railroads, a control office, a field station, a line circuit connecting said control office and said field station, an alternating current source of energy for energizing said line circuit, a first control lever at said control office arranged to selectively energize said line circuit with either polarity of half cycles of alternating current, a second control lever at said control office arranged to selectively energize said line circuit with either polarity of half cycles of alternating current only after a momentary energization of said line circuit with full cycles of alternating current, a track switch at said field station controlled in accordance with the polarity of half cycles of alternating current applied to said line circuit, and means for shifting from the control of said track switch to the control of directional signals at said field station when said line circuit is energized with full cycles of alternating current.

3. In a centralized traffic controlling system for railroads, a control office, a field station, a control line circuit connecting said control office and said field station, two control relays at said field station, a plurality of devices at said field station, means at said control office for energizing either of said control relays over said control line circuit, to control a first of said devices and for 55 momentarily energizing both and then de-energizing either of said control relays to change the control from said first device to a second of said devices at said field station.

4. In a centralized traffic controlling system for railroads, a control office, a field station, a line circuit connecting the control office and the field station, an alternating current source of energy, means at said control office and at said field station for dividing said line circuit into two branches at said control office and at said field station, a relay in series with each of said branches at the field station, means at said control office and at said field station permitting 65 current to flow only in one direction in one of said branches and only in the other direction in the other of said branches at said control office and said field station, means for energizing either of said branches to effect the control of a first device 70 at said field station, means for momentarily en-

ergizing both of said branches and subsequently de-energizing one of said branches to effect the control of a second device at said field station.

5. In a centralized traffic controlling system for railroads, a control office, a distant field station, a line circuit connecting said control office and said field station, a switch control lever at said control office, a means for selecting the direction of pulsating current in said line circuit in accordance with the position of said switch control lever, a signal control lever at said control office, a slow acting relay energized when said signal control lever is in a clear-signal position, a means for applying alternating current to said line circuit during the pick-up period of said slow acting relay, a means for disconnecting said switch control lever from said line circuit and for selecting the direction of pulsating current in said line circuit in accordance with the position of said signal control lever when said slow acting relay is picked up, a track switch and associated signals at said field station, control means for said track switch and signals associated with said line circuit and means for shifting said control means from said track switch to said signals when said line circuit is energized with alternating current.

6. In a railway centralized traffic controlling system, a control office, a distant field station, a line circuit connecting said control office and said field station, a switch control lever arranged to energize said line circuit with either direction of pulsating current, a signal control means at said control office operable to momentarily apply alternating current and to subsequently apply either direction of pulsating current to said line circuit, a first control relay at said field station energized by one direction of pulsating current in said line circuit, a second control relay at said field station energized by the other direction of pulsating current in said line circuit, a control 30 selecting relay energized when said first and said second control relays are both energized, a stick circuit for said control selecting relay completed when either of said control relays are energized, a track switch and associated signals at said field station, contacts on said control relays arranged to control said track switch when said control selecting relay is de-energized and contacts on said control relays arranged to control said signals when said control selecting relay is energized.

7. In a centralized traffic controlling system for railroads, a control office, a field station, a line circuit connecting said control office and said field station, a track switch and associated signals at said field station, switch and signal indicating means at said control office, a track relay at said field station, a track indicating means at said control office, means for conditioning said switch indicating means by selecting the direction of pulsating current in said line circuit according to the position of said track switch, means for changing the condition of said switch indicating means by changing the direction of pulsating current in said line circuit after a period of deenergization, means for conditioning said signal indicating means in response to a condition of said signals by quickly changing the direction of current in said line circuit, and means for conditioning said track indicating means in response to the dropping of said track relay by energizing said line circuit with alternating current.

8. In a railway centralized traffic controlling

in accordance with the new position of the switch control lever.

The present arrangement of circuits also provides that a signal control when once set up by energizing the control line circuit in accordance with a clear position of the signal control lever cannot be removed or cancelled by a subsequent movement of the switch control lever, but remains effective until the signal control lever is returned to its stop position. In other words, the track switch and its control lever must be in corresponding positions in order to complete the signal control circuit as well as the energizing circuit for relay SA as previously described, but when the relay SA has once picked up and allowed a particular signal to be selectively cleared, a subsequent movement of the switch control lever will neither open the signal control circuit nor drop the relay SA. This is accomplished by a stick circuit effective to hold up relay SA whenever contact 106 of lever SGL is in either clear position through a front contact 107 of relay SA, and with the relay SA energized the signal control contact 67 of lever SGL is always connected to the control line wire CL by wires 66, 65 and 108, front contact 7 of relay SA and wires 8 and 9.

Summary

The present invention thus provides a communicating system for centralized traffic control in which the capacity of the individual control and indicating circuits connecting each of the various field stations with the control office is greatly increased. In the particular form shown, a single control line circuit connecting a field station with control office is employed to both effect the control of a track switch as well as the control of certain signals governing traffic movements over this track switch. This control line circuit is normally energized at the control office with half cycles of alternating current, which half cycles are of a uniform polarity which is selected by a contact of the switch control lever through either one of two oppositely arranged rectifiers. The field station end of the control line circuit is divided into two branches, one branch being arranged to conduct one polarity of half cycles of alternating current only by a series rectifier, and the other branch being arranged to conduct the other polarity of half cycles of alternating current only by an oppositely arranged rectifier. Two relays, one in series with each of these branches at the field station, are then selectively energized in accordance with the position of the switch control lever and their position is effective to control the track switch.

It is obvious that both of these series relays at the field station may be energized by applying full cycles of alternating current to the control line circuit, and consequently when a clear signal control is set up at the control office by the switch control lever the field station apparatus is conditioned for the reception of the signal control instead of the switch control by the application of full cycles of alternating current for a predetermined length of time which picks up a control selecting relay at the field station, after which one polarity of half cycles of alternating current is removed from the control line circuit, and the series line relay remaining energized is effective to stick up the control selecting relay and select the clearing of a signal in the direction corresponding to the position of the switch control lever. In canceling a signal clear control,

the control line circuit is de-energized for a predetermined period in which the control selecting relay is dropped at the field station thereby allowing a following energization of the control line circuit to be of a polarity of half cycles of alternating current which is in accordance with the position of the switch control lever.

Indications of the condition of various apparatus at the field station are transmitted to the control office over an indicating line circuit which is substantially the reverse arrangement of the control line circuit, or that is, the indicating line circuit is selectively energized at the field station with either polarity of half cycles or with full cycles of alternating current, and at the control office, the indicating line circuit is divided into two branches each including a series relay and oppositely arranged rectifiers in the same manner as the field station end of the control line circuit. The same rectifiers at both the control office and field station may be employed in both the control and indicating circuits as shown, or of course, separate units may be provided.

The communication of indications of the switch position is accomplished by selecting a definite polarity of half cycles of alternating current in accordance with the operated position of the track switch thereby selecting only one of the series line relays at the control office. Each series line relay at the control office is provided with a slow acting stick repeating relay, which two repeating relays may control a correspondence indicating circuit including a contact of the switch control lever, as shown, or obviously may directly control a two-position switch indicator or two switch indicating lights in a manner well known in the art.

In indicating a change in position of the track switch both series line relays at the control office are de-energized for a period of time before the new series relay is selected which allows the selection of the slow-acting repeating relays to follow in accordance with the selection of the series line relays. However, in indicating a clear signal, the polarity of the half cycles of alternating current is quickly changed without an intervening period of de-energization of the indicating line circuit which does not allow the selection of the slow acting repeating relay to follow in accordance therewith and consequently the selection of the series line relays is out of correspondence with the energization of their slow acting repeating relays. A signal indicating light at the control office is then energized by a circuit completed by this out-of-correspondence condition between the series line relays and their stick repeating relays, but when the clear signal at the field station is returned to stop, the polarity on the indicating line circuit is changed back to its original polarity of half cycles of alternating current thereby extinguishing the clear signal indication at the control office by operating the series line relays into correspondence with the energization of their stick repeating relays.

An indication of a third device at the field station, which may be a track relay, is transmitted to the control office by a circuit arrangement whereby the full cycles of alternating current are applied to the indicating line circuit in the same manner as described in connection with the control line circuit. These full cycles of alternating current are effective at the control office to pick up both series line relays, and an indication of the dropping of the track relay at the field station is given by an indicating light energized by

- system, a control office, a field station, a line circuit connecting said control office and said field station, a first line relay at said control office energized by one direction of current in said line circuit, a second line relay at said control office energized by the other direction of current in said line circuit, a first slow acting relay picked up by said first line relay, a second slow acting relay picked up by said second line relay, stick circuit means for maintaining either of said slow acting relays energized when the direction of current in said line circuit is quickly changed after such slow acting relay is picked up, a plurality of indicating means at said control office controlled by said slow acting relays, and means for causing current to flow in said line circuit in one direction, in the other direction, in each direction alternately, for opening said line circuit or for quickly changing the direction of current in accordance with various conditions at said field station to distinctively control said indicating means at said control office. 10
9. In a railway centralized traffic controlling system, a control office, a field station, a first line circuit connecting said control office and said field station, a track switch and associated signals at said field station, an alternating current source of energy, means including rectifiers at said control office and rectifiers at said field station for controlling either said track switch or said signals from said control office in accordance with the energization of said first line circuit, a second line circuit connecting said control office and said field station, and means including rectifiers at said control office and rectifiers at said field station for indicating at said control office the position of said track switch and said signals and the presence of a train on said track switch in accordance with the energization of said second line circuit. 20
10. In a railway centralized controlling system, a control office, a field station, a track switch and associated signals at said field station, a track switch control lever and a signal control lever at said control office, a first line circuit and a second line circuit each connecting said control office and said field station, means for indicating at the control office the condition of said track switch and associated signals over said second line circuit, means for controlling said signals over said first line circuit only when the indicated condition of said track switch corresponds to the position of said track switch control lever, and means for controlling said track switch over said first line circuit only when said signals are placed at stop. 30
11. In a railway centralized traffic controlling system, a control office, a field station, a track switch and associated signals at said field station, a track switch control lever and a signal control lever at said control office, a first line circuit and a second line circuit each connecting said control office and said field station, means for indicating at the control office the condition of said track switch and associated signals over said second line circuit, means for clearing said signals over said first line circuit only when the indicated condition of said track switch corresponds to the position of said track switch control lever, means for retaining an existing cleared signal irrespective of a subsequent movement of said track switch control lever, and means for controlling said track switch by said track switch control lever over said first line circuit. 40
- 75 12. In combination, a control point, a distant location, two line circuits connecting said control point and said distant location, rectifier units at said control point and at said distant location, means including one of said line circuits and said rectifier units for controlling a plurality of devices at said distant location from said control point, and means including the other of said line circuits and said rectifier units for indicating at the control point the condition of said plurality of devices at said distant location. 10
13. In combination, two spaced locations, a line circuit connecting said spaced locations, first and second devices at one of said spaced locations, means for at times controlling said first device by energizing said line circuit with pulsating current of one or the other polarity at said other location, means for at times controlling said second device by energizing said line circuit with pulsating current with one or the other polarity at said other location, and means for automatically selecting whether said first or said second device is to be controlled by the particular energization of said line circuit. 15
14. In combination, two spaced locations, a line circuit connecting said spaced locations, first and second devices at one of said spaced locations, means for at times controlling said first device by energizing said line circuit with pulsating current of one or the other polarity at said other location, means for at times controlling said second device by energizing said line circuit with pulsating current with one or the other polarity at said other location, and means for determining that said second device is to be controlled, which means is rendered effective by temporarily energizing said line circuit with alternating current. 25
15. In combination, two spaced locations, a line circuit connecting said spaced locations, first and second devices at one of said spaced locations, means for at times controlling said first device by energizing said line circuit with pulsating current of one or the other polarity at said other location, means for at times controlling said second device by energizing said line circuit with pulsating current with one or the other polarity at said other location, and means for determining that said second device is to be controlled, which means is rendered effective by temporarily energizing said line circuit with alternating current. 30
16. In combination, two neutral relays which can be selectively controlled so that either or both may be energized or both may be deenergized, a first and a second device, means for distinctively controlling said first device in accordance with which particular one of said relays is energized after both said relays have been deenergized, and means for distinctively controlling said second device in accordance with which particular one of said relays is energized after both of said relays have been energized. 40
17. In combination, two neutral relays which can be selectively controlled so that either or both may be energized or both may be deenergized, a first and a second device, means for distinctively controlling said first device in accordance with which particular one of said relays is energized only after both said relays have been deenergized, and means for distinctively controlling said second device in accordance with which particular one of said relays is energized only after both of said relays have been energized. 50
18. In combination, two neutral relays which 60

can be selectively controlled so that either or both may be energized or both may be deenergized, a stick relay, a pick up circuit for said stick relay closed only when both said neutral relays are energized, a stick circuit for said stick relay including its own front contact in series with a front contact of each of said neutral relays in multiple, whereby said stick relay is deenergized by deenergization of both of said neutral relays 5 and whereby said stick relay is picked up by energization of both said neutral relays and left maintained energized by energization by either of said neutral relays, a first and a second device, means for selectively controlling said first device in accordance with the selective energization of said neutral relays when said stick relay is deenergized, and means for selectively controlling said second device in accordance with the selective energization of said neutral relays when said stick 10 relay is energized.

19. In combination, two neutral relays which can be selectively controlled so that either or both may be energized or both may be deenergized, two slow acting stick relays, a pick up circuit for one 25 of said stick relays including a front contact of one of said neutral relays and a back contact of the other of said stick relays, a pick up circuit for said other of said stick relays including a front contact of the other of said neutral relays and a back contact of said one stick relay, a stick circuit for said one stick relay including its 30 own front contact and a front contact of said other neutral relay, a stick circuit for said other stick relay including its own front contact and a front contact of said one neutral relay, and electro-responsive means controlled by said relays 35 jointly.

20. In combination; a line circuit connecting two spaced locations; two manually operable 40 levers at one of the locations, each of said levers for at times selectively energizing said line circuit with pulsing current of one polarity or the other; electro-responsive means at the other of the locations distinctively responsive to the polarity of 45 energization of said line circuit; means at the one location for at times automatically causing said line circuit to be successively energized in accordance with said two manually operable levers with an intervening energization of alternating current 50 on said line circuit; first and second devices at the other location, said first device being normally under the control of said electro-responsive means; and means controlled by said electro-responsive means during the energization of said 55 line circuit with alternating current for automatically causing said second device to be placed un-

der the control of said electro-responsive means.

21. In a centralized traffic controlling system for railroads; a track switch operable to normal and reverse positions; a signal for governing traffic over said track switch; a switch control lever 5 having normal and reverse positions; a signal control lever having clear and stop positions; a selector relay; a pick up circuit for said selector relay closed only when said track switch and switch control lever are in corresponding normal 10 or reverse positions and said signal lever is in a clear position; a stick circuit for said selector relay including its own front contact and a contact on said signal lever closed when such signal lever is in a clear position, whereby said relay when 15 once picked up is fully dependent for its energization on said signal lever; means for controlling said track switch by said switch lever effective only when said selector relay is deenergized; and means for controlling said signal by said signal lever effective only when said selector relay is picked up. 20

22. In a centralized traffic controlling system for railroads; a control office; a field station; a line circuit connecting said control office and said field station; an alternating current source of energy for energizing said line circuit; a railroad track switch at the field station; a signal at the field station; switch contacts operated by said track switch to normal, reverse and open unlocked positions; means including said switch contacts 25 for selectively allowing said line circuit to be energized from said source with either polarity of half cycles of alternating current in accordance with the position of said track switch or to be deenergized; signal contacts operated in accordance with 30 the condition of said signal; means including said signal contacts for reversing the polarity of energization of said line circuit with half cycles of alternating current applied through said switch contacts, whereby said switch contacts may reverse the polarity of half cycles only after a prolonged deenergization of said line circuit, and whereby said signal contacts can quickly reverse the polarity of energization of said line circuit; 35 electro-responsive means at the control office responsive to the polarity of energization of said line circuit; means controlled by said electro-responsive means to register whether a reversal of polarity on said line circuit has been after a prolonged deenergization or has been quickly accomplished; and indicator means controlled by said electro-responsive means and said registering means. 40

EDWIN O. BLODGETT. 55

DISCLAIMER

2,042,450.—*Edwin O. Blodgett*, Rochester, N. Y. CENTRALIZED TRAFFIC CONTROL-LING SYSTEM FOR RAILROADS. Patent dated June 2, 1936. Disclaimer filed April 12, 1937, by the assignee, *General Railway Signal Company*.

Hereby enters this disclaimer by disclaiming from claim 1 any system, except wherein the "means for controlling a first device" and the "means for controlling a second device" are separately and independently operable manually; by disclaiming from claims 13 and 14 any system, except wherein the "means for at times controlling said first device" and the "means for at times controlling said second device" are separately and independently operable manually; by disclaiming from claim 9 any system, except wherein the "second line circuit" includes a different line wire connecting the "control office" and the "field station" than is included in the "first line circuit"; and by disclaiming from claims 16 and 17 any system, except wherein the devices defined as "a first and a second device" are a switch machine and signals associated with said switch machine.
